UNITED STATES PATENT OFFICE.

DAVID G. MELVILLE, OF MEDFORD, ASSIGNOR TO THE ROXBURY CARPET COMPANY, OF BOSTON, MASSACHUSETTS.

DESIGN FOR A CARPET.

SPECIFICATION forming part of Design No. 15,212, dated August 5, 1884.

Application filed June 9, 1884. Term of patent 3½ years.

To all whom it may concern:

Be it known that I, DAVID G. MELVILLE, of Medford, in the county of Middlesex and State of Massachusetts, have invented a new and original Design for Carpets, of which the following is a specification.

The nature of my design is fully shown in the accompanying photographic illustration.

The design is composed of the thickly-aranged conventionalized blossoms and the foliage partly covering said blossoms, as shown.

I claim—

The design for a carpet, substantially as shown and described.

In testimony whereof I have signed my name to this specification, in the presence of two subscribing witnesses, this 5th day of June, 1884.

DAVID G. MELVILLE.

Witnesses:

DAVID McNAIR,

WALTER J. GADSBY.
